[57] CLAIM

The ornamental design for a closure assembly for a
refuse and recycling receptacle, as shown and de-
scribed.

DESCRIPTION

FIG. 1 is a top plan view of a closure assembly for a
refuse and recycling receptacle showing our new de-
sign;

FIG. 2 is a front elevational view thereof;

FIG. 3 is a rear elevational view thereof; and,

FIG. 4 is a side elevational view thereof, the opposite
side elevational view being a mirror image of that
shown.

FIG. 1

FIG. 2

FIG. 3

FIG. 4
